[57] ABSTRACT

Process for preparing an ester by reacting a carboxylic acid with an O-lower alkyl imino ether.

8 Claims, No Drawings

ESTERIFICATION OF CARBOXYLIC ACIDS BY
REACTION WITH O-LOWER ALKYL IMINO
ETHERS

BACKGROUND OF THE INVENTION

This invention relates to a process for esterifying a carboxylic acid.

In the past, esterification reactions have typically involved reacting an acid with an alcohol in the presence of a strong mineral acid, added to promote the reaction. In selected cases, the use of a strong acid provides relatively high yields of ester. However, in many other cases, the use of a strong acid medium causes significant difficulties which adversely affect the yields and purities of esters obtained by these processes. For example, using a strongly acidic medium should not be considered when either the acid or the ester is prone to acid catalyzed side reactions such as dehydration, isomerization, or hydrolysis. Furthermore, the use of a strong acid medium is not appropriate when it is desired to carry out the esterification in reaction vessels which are not specially resistant to the effects of strong acids.

In order to overcome the disadvantages of using an acid to promote esterification, processes have been developed which utilize substantially neutral reaction conditions, i.e., a pH of about 6 to 8. Such processes have typically involved reacting a carboxylic acid with an alkylating agent such as triethyloxonium fluoroborate or diazomethane. However, serious problems have also been associated with the use of such esterifying agents. Among the problems have been the high toxicity of certain agents, the explosiveness of certain agents, and/or the tendency of certain alkylating agents to decompose in the presence of moisture.

There has been a need therefore for an improved esterification procedure which provides high yields, while at the same time, allowing the reaction to be carried out under essentially neutral reaction conditions, without the accompanying problems which have heretofore been associated with alkylating agents.

SUMMARY OF THE INVENTION

In accordance with this invention, a process is provided for preparing an ester, comprising reacting a carboxylic acid with an O-lower alkyl imino ether of the formula:

wherein R is an unsubstituted lower alkyl and m is an integer of from 1 to 3.

By this process, an ester can be readily prepared in high yields and with a high degree of purity under substantially neutral reaction conditions, without the use of highly toxic, explosive and/or unstable alkylating agents.

DETAILED DESCRIPTION OF THE INVENTION

This invention relates to a process for preparing an ester by reacting a carboxylic acid with an O-lower alkyl imino ether of formula I. In carrying out the ester-

ification of this application, the preferred O-lower alkyl imino ether is the ether of formula I wherein "m" is 3, i.e., an O-lower alkylcaprolactim. By this process, esterification can be carried out in high yields, under substantially neutral reaction conditions.

As used throughout this application, the term "carboxylic acid" comprehends any carboxylic acid containing one to four carboxy groups, including aliphatic, aromatic and heterocyclic acids. Among the carboxylic acids in this application are the acids of the formula:

wherein n is an integer of from 1 to 4 inclusive and is equal to the valence of R₁; and R₁ is hydrogen, alkyl, cycloalkyl, alkenyl, cycloalkenyl, alkynyl, cycloalkynyl or aryl.

Among the carboxylic acid of formula II are included:

- benzoic acid,
- isophthalic acid,
- decanoic acid,
- 3-methyl octanoic acid,
- cyclopentanecarboxylic acid,
- 4-toluenecarboxylic acid,
- 3,5-xylenecarboxylic acid,
- 1,2,3-benzenetricarboxylic acid,
- 1,2,4,5-benzenetetracarboxylic acid,
- furoic acid,
- 1,8-octanedicarboxylic acid,
- 1,2,4,5-cyclooctanetetracarboxylic acid,
- cycloecosanecarboxylic acid,
- arachidonic acid,
- 2,3,6,7-anthracenetetracarboxylic acid,
- vitamin A acid,
- ricinoleic acid,
- oxalic acid,
- sebacic acid,
- linoleic acid,
- o-chlorobenzoic acid,
- m-bromobenzoic acid,
- p-nitrobenzoic acid,
- p-hydroxybenzoic acid,
- m-methoxybenzoic acid,
- m-nitrobenzoic acid,
- cholanic acid,
- formic acid,
- acetic acid,
- pivalic acid,
- propionic acid,
- heptanoic acid,
- palmitic acid,
- stearic acid,
- succinic acid,
- oleic acid,
- fumaric acid,
- maleic acid,
- cyclopentenylacetic acid,
- cyclohexylpropionic acid,
- phenylacetic acid,
- naphthylpropionic acid, and
- naphthoic acid.

Among the preferred carboxylic acids of formula II are the compounds of the formula:

substituted with one or more groups, such as alkoxy, alkenyloxy, alkynyoxy, hydroxy, oxo, cycloalkyl, cycloalkenyl, cycloalkynyl, cycloalkoxy, cycloalkenyloxy and aryl groups. In this application, the preferred alkynyl groups are the unsubstituted lower alkynyl groups of 2 to 6 carbon atoms, such as ethynyl and propynyl.

wherein n' is an integer of from 1 to 2 and R_1' is unsubstituted alkyl, unsubstituted alkenyl, aryl, aryl lower alkyl or aryl lower alkenyl.

Particularly preferred are the carboxylic acids of the formula:

wherein R_1'' is unsubstituted lower alkyl, carboxy lower alkyl, unsubstituted lower alkenyl, unsubstituted aryl, lower alkoxy or hydroxy substituted aryl, unsubstituted aryl lower alkyl, lower alkoxy or hydroxy substituted aryl lower alkyl, unsubstituted aryl lower alkenyl, or lower alkoxy or hydroxy, substituted aryl lower alkenyl.

As also used throughout this application, the term "alkyl" comprehends straight chain and branched chain, saturated aliphatic hydrocarbon groups of 1 to 20 carbon atoms. The alkyl groups of this application may be unsubstituted or substituted with one or more groups such as alkoxy, alkenyloxy, alkynyoxy, hydroxy, oxo, cycloalkyl, cycloalkenyl, cycloalkynyl, cycloalkoxy, cycloalkenyloxy, cycloalkynyoxy and aryl groups. In this application, the preferred alkyl groups are the unsubstituted lower alkyl groups of 1 to 6 carbon atoms, such as methyl, ethyl and isopropyl. With regard to the unsubstituted lower alkyl groups represented by "R" in formula I, the particularly preferred alkyl groups are the primary and secondary, unsubstituted, lower alkyl groups, quite particularly methyl and ethyl.

Also throughout this application, the term "cycloalkyl" comprehends saturated, aliphatic hydrocarbon groups of 3 to 20 carbon atoms, containing one or more, saturated, mononuclear or polynuclear, cycloaliphatic moieties, such as cyclopropyl and cyclohexyl.

Also in this application, the term "alkenyl" comprehends straight chain and branched chain, aliphatic hydrocarbon groups of 2 to 20 carbon atoms which contain one or more double bonds. The alkenyl groups of this application can be unsubstituted or substituted with one or more groups, such as alkoxy, alkenyloxy, alkynyoxy, hydroxy, oxo, cycloalkyl, cycloalkenyl, cycloalkynyl, cycloalkoxy, cycloalkenyloxy, cycloalkynyoxy and aryl groups. In this application, the preferred alkenyl groups are the unsubstituted lower alkenyl groups of 2 to 6 carbon atoms such as vinyl and allyl.

Also herein, the term "cycloalkenyl" comprehends aliphatic hydrocarbon groups of 3 to 20 carbon atoms containing one or more, mononuclear or polynuclear, cycloaliphatic moieties, of 3 to 18 carbon atoms, with at least one of the cycloaliphatic moieties containing one or more double bonds, such as cyclohexenyl.

As further used throughout this application, the term "alkynyl" comprehends straight chain and branched chain, aliphatic hydrocarbon groups of 2 to 20 carbon atoms which contain one or more triple bonds. The alkynyl groups of this application can be unsubstituted or

5 substituted with one or more groups, such as alkoxy, alkenyloxy, alkynyoxy, hydroxy, oxo, cycloalkyl, cycloalkenyl, cycloalkynyl, cycloalkoxy, cycloalkenyloxy and aryl groups. In this application, the preferred alkynyl groups are the unsubstituted lower alkynyl groups of 2 to 6 carbon atoms, such as ethynyl and propynyl.

Further throughout this application, the term "cycloalkynyl" comprehends aliphatic hydrocarbon groups of 3 to 20 carbon atoms containing one or more, mononuclear or polynuclear, cycloaliphatic moieties, with at least one of the cycloaliphatic moieties containing one or more triple bonds, such as cyclohexynyl.

Further herein, the term "aryl" comprehends 10 mononuclear and polynuclear aromatic hydrocarbon groups such as phenyl, tolyl, etc., which can be unsubstituted or substituted in one or more positions, taken individually or together, with groups such as lower alkylenedioxy, halogen, nitro, alkoxy, alkenyloxy, alkynyoxy, alkyl, alkenyl, alkynyl, cycloalkenyloxy, cycloalkynyoxy, cycloalkyl, cycloalkenyl, cycloalkynyl, hydroxy and oxo groups. Among the polynuclear aryl groups are groups such as naphthyl, anthryl, phenanthryl, azulyl, etc., which may be unsubstituted or substituted 15 with one or more of the aforementioned moieties. In this application, the preferred aryl groups are the unsubstituted aryl groups and the aryl groups, substituted with a hydroxy or lower alkoxy group, containing 6 to 20 10 carbon atoms.

25 As still further used throughout this application, the term "primary alkyl group" comprehends groups 30 wherein alkyl is as defined above and wherein the α -carbon atom of the group is a primary carbon atom. Also herein, the term "secondary alkyl group" comprehends groups wherein alkyl is as defined above and 35 wherein the α -carbon atom of the group is a secondary carbon atom.

Still further herein, the term "halogen" or "halo" 40 when not expressly stated otherwise, includes all four halogens, i.e., chlorine, bromine, fluorine and iodine. The term "lower alkylenedioxy" comprehends groups having 1 to 4 carbon atoms such as methylenedioxy.

45 As still further used herein, the terms "alkoxy", "alkenyloxy", "alkynyoxy", "cycloalkoxy", "cycloalkenyloxy" and "cycloalkynyoxy" comprehends the groups 50 wherein the alkyl, alkenyl, alkynyl, cycloalkyl, cycloalkenyl and cycloalkynyl moieties are as defined above. Still further herein, terms such as "aryl lower alkyl", "aryl lower alkenyl", and "carboxy lower alkyl" comprehend alkyl and alkenyl groups which are substituted with only an aryl group or a carboxy group and wherein the alkyl and aryl moieties are as defined above.

55 In carrying out the process of this invention, temperature and pressure are not critical, and the reaction can be conveniently carried out at above about 40°C. and at atmospheric pressure. Preferably, the reaction is carried out at a temperature of about 60°C. to the reflux temperature of the reaction mixture, with a temperature of about 80° to 85°C. being particularly preferred.

In carrying out this process, any carboxylic acid can be utilized, and the ratio of the carboxylic acid to the O-lower alkyl imino ether of formula I is not critical. In this process, it is preferred to utilize at least 1 mole equivalent of the O-lower alkyl imino ether for each mole equivalent of carboxylic acid, with about 1 mole equivalent of each reactant being particularly pre-

ferred. However, if desired, greater amounts of the O-lower alkyl imino ether can also be conveniently utilized.

This process can, if desired, be carried out in an inert organic solvent. In this process, any conventional inert organic solvent can be utilized, such as benzene, toluene, methylene chloride or chloroform. Preferably, the

ester was purified by crystallization if the ester was a solid, utilizing an appropriate solvent, or by distillation under reduced pressure if the ester was a liquid to give analytically pure material.

The table which follows summarizes the results of the example.

Table of Esterification of Carboxylic Acids with O-Methylcaprolactim

Carboxylic Acid	Temp., °C.	Conditions	Time, hr.	Yield, % ³	Methyl ester B.p. or M.p., °C.
Benzoic acid	80-85		16	91	B.p. = 101-102/24mm
p-Methoxyphenyl acetic acid	80-85		6	76	B.p. = 150-151/15mm
2-Naphthoic acid	80-85		16	96	M.p. = 75-76 ¹
Adipic acid	80-85		16	72	B.p. = 95/9mm
Dimethyl acrylic acid	80-85		16	78	B.p. = 130-135
Salicylic acid	80-85		16	80	B.p. = 87-88/7mm
p-Methoxycinnamic acid	80-85		16	73	M.p. = 88-90 ²

¹Residue after diethyl ether removed by distillation. Crystallization not required.

²Crystallized from ethanol.

³Based on isolated material.

process of this invention is carried out without utilizing any solvent, using only the carboxylic acid and the O-lower alkyl imino ether of formula I.

By the process of this invention, yields of about 70 to 25 percent of the ester can be obtained. The ester

EXAMPLE 2

Utilizing the procedure of Example 1, O-lower alkyl imino ethers were reacted with benzoic acid. The table which follows summarizes the results obtained.

Table of Esterification of Benzoic Acid by O-alkyl imino ethers

Imino Ether	Molar ratio of imino ether to Benzoic Acid	Temp., °C.	Time, Hr.	Yield of isolated methyl benzoate %
2-methoxy-1-pyrroline	2	85-90	20	78
2-methoxy-3,4,5,6-tetrahydropyridine	1	85-90	24	70
O-methylcaprolactim	2	85-90	20	92

which is produced by this process can be readily separated from the water soluble by-product of the process, i.e., a lactam of the formula:

III 45

wherein *m* is as above.

The crude ester can then be purified in a conventional manner by crystallization or by distillation to give a product having a high degree of purity.

The O-alkyl imino ethers of formula I can be obtained by a direct O-alkylation of the lactam of formula III in accordance with the procedure of Benson and Crains, 70 *Journal of the American Chemical Society* 2115 (1948).

The examples which follow further illustrate this invention.

EXAMPLE 1

A carboxylic acid (0.1 mol) and O-methylcaprolactim (0.1 mol per carboxyl group in the acid) were heated at 80° to 85°C. from 6-16 hrs. The resulting liquid was diluted with diethyl ether, washed with 1N aqueous sodium hydroxide solution, washed with water, and dried over MgSO₄. The MgSO₄ was fil-

40 What is claimed is:

1. A process for preparing an ester comprising: reacting a carboxylic acid with an O-lower alkyl imino ether of the formula:

50 wherein R is an unsubstituted lower alkyl and *m* is an integer of 1 to 3; wherein said carboxylic acid is of the formula:

55 60 wherein *n* is an integer of from 1 to 4 inclusive and is equal to the valence of R₁; and R₁ is hydrogen, substituted or unsubstituted alkyl having from 1 to 20 carbon atoms, cycloalkyl having from 3 to 20 carbon atoms, unsubstituted or substituted alkenyl having from 2 to 20 carbon atoms, cycloalkenyl having from 3 to 20 carbon atoms, substituted or unsubstituted alkynyl having from 2 to 20 carbon atoms, cycloalkynyl having

from 3 to 20 carbon atoms, unsubstituted or substituted aryl selected from the group consisting of phenyl, naphthyl, anthryl, phenanthryl and azulyl

2. The process of claim 1 wherein said process is carried out at about 60°C. to the reflux temperature of the reaction mixture.

3. The process of claim 2 wherein said process is carried out at about 80° to 85°C.

4. The process of claim 1 wherein at least about one mol of said O-lower alkyl imino ether is utilized per mol 10 equivalent of said acid.

5. The process of claim 1 wherein said O-lower alkyl imino ether is an O-alkylcaprolactim.

6. The process of claim 5 wherein R is methyl or ethyl.

7. The process of claim 1 wherein said carboxylic acid is of the formula:

20

wherein R_1'' is unsubstituted lower alkyl, carboxy lower alkyl, unsubstituted lower alkenyl, unsubstituted aryl, lower alkoxy or hydroxy substituted aryl, unsubstituted aryl lower alkyl, lower alkoxy or hydroxy substituted aryl lower alkyl, unsubstituted aryl lower alkenyl, or lower alkoxy or hydroxy substituted aryl lower alkenyl.
